CATCH MECHANISM

Claude B. Elerding, Seattle, Wash.

Application June 9, 1952, Serial No. 292,543

6 Claims. (Cl. 217—60)

1

This invention relates to improvements in mechanisms which are generally known as "catches" or as "latch devices," and it has reference to a latch mechanism for supporting a hinged lid or cover at any one of a plurality of raised or open positions. More specifically, the invention relates to a latching mechanism that is designed for use in connection with a school desk equipped with a top that is hingedly mounted for tilting adjustment; the present latching mechanism serving as a means for supporting the desk top at any one of a plurality of predetermined positions of inclination to which it may be adjusted to suit the convenience of the user.

It is the principal object of the present invention to provide a simple, relatively inexpensive and positively acting latch mechanism of the above character that is rendered automatic in its setting and releasing operations through the raising and lowering movements of the desk top to which it is attached.

Another object of the invention is to provide a latching mechanism including a pivoted latch dog that is mounted on a relatively stationary member of the desk, and a latch bar that is attached at one end to the desk top, and which moves relative to the pivoted dog incident to raising and lowering of the desk top; the bar being formed with notches in spaced relationship therealong, in which the latch dog is selectively engageable to retain the desk top at the desired inclination, and the mechanism being further characterized by the inclusion of novel devices associated with the bar and with the latch dog which make possible the automatic release of the dog for a change in adjustment of the desk top and also an automatic engagement of the dog to secure an adjustment after it has been made.

Still further objects and advantages of the present invention reside in the specific details of construction of, and in the combination of those parts that co-act for the automatic release and resetting of the latch dog.

In accomplishing the above mentioned and other objects of the invention, I have provided the improved details of construction, the preferred forms of which are illustrated in the accompanying drawings, wherein—

Fig. 1 is a side view of a portion of a desk having a top that is mounted for tilting adjustment and is adapted to be selectively supported at different positions of inclination by a latching mechanism embodying the improvements of the present invention therein.

Fig. 2 is top view of the latching mechanism as

2

applied to the desk; the top of the desk being indicated only in dotted lines for a better showing of the latching mechanism.

Fig. 3 is a side view of the latch bar and latch dog in the relationship they assume with the desk top in a fully lowered position.

Fig. 4 is a cross-section of the latch bar and dog as seen on the line 4—4 in Fig. 3.

Fig. 5 is a fragmental elevation of a portion of the latch bar and latch dog, showing the latter in holding contact with a shoulder on the bar; the parts being in the relationship in which they are shown in full lines in Fig. 1.

Fig. 6 is a view similar to that of Fig. 5, illustrating the upward actuation of the latch dog as effected by a limited upward adjustment of the desk top, preparatory to lowering it in its position of support.

Fig. 7 is a similar view illustrating the re-engaging of the latch dog with the latch bar for support of the desk top at the lowered position of support.

Fig. 8 is a cross-section of the latch bar and dog, as seen on line 8—8 in Fig. 6.

Fig. 9 is a perspective view of parts of the latch dog in disassembled relationship.

As a showing of a typical use of the present mechanism, it has been illustrated in connection with a school desk that is equipped with a top that is hingedly mounted for adjustment about the hinge axis to different angles of inclination and supported at any one of a plurality of definite or pre-determined positions. It is to be understood, however, that the present mechanism is applicable to various other articles, for example, it may be used in connection with the lid of a trunk, chest or other container, or as a means of support for the door panel of the rear compartment of an automobile; the present illustrations, however, being typical of the various adaptations and uses of the mechanism.

Referring more in detail to the drawings—

In Fig. 1, a school desk is designated generally by reference numeral 10. It comprises a frame structure having a cross member 12 to which the desk top or cover 13 is hingedly attached by a hinge designated in its entirety by numeral 15. The hinge provides that the top can be adjusted upwardly from a horizontal position of rest on the desk frame, for support at any one of a plurality of selected angles of inclination.

The present latch mechanism comprises two principal parts which are herein referred to, respectively, as the latch bar and the latch dog.

The latch bar, which is designated in its entirety

by reference numeral 16, comprises a flat, rigid and somewhat elongated bar, preferably of metal, pivotally attached at its forward end by a pivot pin 17 to a bracket 18 that, in turn, is rigidly attached to the under side of the desk top at a substantial distance from the hinge as has been shown in Fig. 1. The bar 16 is formed with a straight, longitudinal slot 19, extending substantially the full length of the bar. Extending through this slot is a pivot member 20, which may be a pin, bolt, stud or shaft that is rigidly mounted in the frame structure of the desk parallel with the hinge axis, as seen in Fig. 2. The position of the latch bar 16, as thus attached to the desk top is such that in the raising and lowering of the desk top, the bar is caused to move longitudinally in guided support by the pivot member 20. In the present instance, when the lid is in its lowered, horizontal position of rest on the desk frame, the bar 16 assumes the horizontal dotted line position in which it is shown in Fig. 1, and when the lid is raised to a 45° angle, the bar will assume the substantially vertical full line position. Raising of desk top beyond about a 50° angle is, in this instance, limited by the lower end of the bar slot 19 engaging with the pivot stud 20.

Associated with the latch bar 16 and pivot 20 is the latch dog which in Figs. 1, 2 and 3 is designated in its entirety by reference numeral 25. More specifically described, the latch dog comprises a frame member that preferably is blanked as a single piece from sheet metal, then bent substantially to U-form. In its final form it comprises spaced, parallel opposite side plates 26-26, connected across the forward edges of their lower ends, with reference to its showing in the present drawings, by an integral strap 27. At the rear edges, of the lower ends of these side plates, wings 28-28 are inwardly turned into end to end contact. Extended between the upper end portions of the side plates 26-26 of the latch dog, is a tubular bushing 29; the opposite end portions of which extend through and are secured in the plates as shown in Fig. 8. This tubular bushing is rotatably fitted on the pivot member 20, and it extends through the slot 19 of the bar 16. Medially of its ends, the bushing is formed with a squared portion 29x that is contained in the slot. Adjacent its opposite ends, the bushing is slightly reduced in external diameter to provide mounting portions for the plates 26-26, and to form shoulders against which the plates may be engaged to be thereby held in a definite spaced relationship.

Mounted on the bushing, at opposite sides of its squared medial portion 29x, and flatly engaged against the opposite side faces of the bar 16, are flat washers 30-30. Disposed against these washers are flat spring metal strips 31-31, each strip having a circular enlargement 31' at one end formed with a central hole 31h for receiving the end portion of the bushing therethrough. Each spring strip extends along the inside face of the corresponding side plate of the latch dog to the lower end of the latter and is thereby confined between the cross strap 27 and an inturned wing 28. Mounted under compression on the bushing, between the side plates of the latch dog and the head portions of the spring strips 31-31, are corrugated spring washers 35-35, which yieldingly resist outward springing of the spring strips, as assembled with the latch dog. The normal relationship of spring strips 31-31 to the side members of the latch dog is as shown in Fig. 8.

The latch bar 16, as seen in Figs. 1 and 3, is formed in its lower edge, at predetermined intervals therealong, with recesses or notches 40; each notch having one edge perpendicular to the edge of the bar to provide an abutment shoulder 41, and having a gradually sloping and rather elongated opposite edge 42. All shoulders 41, as noted in Fig. 1, face toward the lower end of the bar and they are so located in the bar that when cross strap 27 of the latch dog is engaged with any one of them, the desk top will be supported at a definite angle of inclination.

While I have herein shown the bar 16 as being equipped with only three notches, more or less might be employed as desired or required.

It will be understood that when the top 13 is raised and the cross strap 27 of the latch dog is holdingly engaged against the end shoulder 41 of a notch, for example as noted in Fig. 1 or in Fig. 5, the desk top will be supported in an inclined position. Also, it will be understood that to lower the desk top, from any inclined position of support, it will be necessary that the latch dog be disengaged from the shoulder and then so positioned relative to the bar that the cross strap 27 will clear the bar for movement. The present invention is characterized by the provision of friction means on the bar 16 to accomplish the disengaging of the latch dog and also its re-setting merely by raising and lowering movements of the desk top. These operations will now be described:

Starting with the desk top in a lowered, horizontal position of rest and the latch bar 16 and latch dog in the relationship in which they are shown in Figs. 2 and 3, and assuming that it is desired to adjust the desk top for support at any one of its selected angles of support; the top is raised by swinging its free edge upwardly about the hinge axis. As the desk top moves upwardly, the bar 16 slides endwise through the latch, as guided by the pivot member, and its free end moves toward the latch dog. When the desk top has been raised to such extent that the particular shoulder 41 that is to be engaged by the dog for support of the top has passed through and slightly beyond the latch dog, then the desk top is slightly lowered, and the cross strap 27 of the latch dog is engaged with the shoulder. To insure such engagement of the strap with any selected shoulder, I have provided the bar 16 with friction knobs 38, well shown in Figs. 3 and 4. These knobs are of metal and in the form of hemispheres projecting in alignment from the opposite sides of the bar 16 immediately above each of the shoulders 41. These knobs project sufficiently from the bar surface that incident to the shifting of the bar 16 lengthwise, and the passing of any set of knobs between the opposite side plates of the latch dog, they will frictionally contact with the under sides of the outwardly yieldable spring strips 31-31 thus through them to drag the lower end of the latch dog in the direction of travel of the bar.

It is of importance to understand that if the desk top is swung upwardly from any position of support and the bar 16 is thereby caused to move to such extent that at least one set of friction knobs is caused to pass from a position below the latch dog to a position above it; then reverse travel of the bar 16 will cause the first set of knobs that engages the latch to swing it back into holding contact with the notch shoulder adjacent that set of knobs. However, if the desk top is moved upwardly only to such limited extent that the immediately adjacent knobs will engage

the dog and swing it to that position of release, in which it is shown in Fig. 6, and no farther, then upon lowering movement of the top the dog will remain in that position and the bar 16 will slide freely through the latch and will not be stopped until the latch is actuated to holding position by the next higher set of knobs.

Therefore, it will be understood that if it is desired to lower the desk top from the full line position shown in Fig. 1 to the next lower dotted line position, it is only necessary to swing the desk top upwardly through a slight angle, thus to cause the friction knobs, which are then immediately below the latch lever to engage the spring strips, but not to pass beyond them, and rotate the latch dog, as from position of Fig. 5, to position of Fig. 6, then to lower the top. In the lowering, the bar 16 moves downwardly and the friction knobs merely disengage the latch dog without causing re-setting movement. Therefore, the bar 16 can continue to move downwardly through the latch to bring the next higher notch thereof into position. When the friction knobs associated with this next higher notch come into frictional contact with the latch dog springs 31 they rotate the latch downwardly to holding position and its cross strap 27 engages with the notch shoulder, for example, as in Fig. 7 to support the top.

To release the latch dog as required for a further lowering of the desk top, it is only necessary to swing the top upwardly through that limited angle required to cause the friction knobs, which are then immediately below the latch lever, to again engage the spring strip and rotate the latch dog to a position of release, then to lower the top and cause the bar 16 to move downwardly through the latch and the next higher set of friction knobs thereon to be engaged with the spring strips 31 of the latch to swing it to holding position in the same manner as previously described.

Regardless of the angular position at which the desk top may be supported by the bar and latch dog, the latter may be released from the bar for a lowering adjustment of the top merely by effecting that slight upward swing of the top that causes the latch dog to be moved to "release" position but without the actuating knobs 50 passing the spring strips, then swinging the top downwardly.

Upward adjustment of the desk top from any position to full extent can be made without interruption, but positions of support are established only by first raising the top to a position slightly beyond the desired inclination, then lowering it to cause the friction knobs corresponding to that position of support, to engage and swing the latch dog to holding position.

The functional operations of the latch mechanism are by reason of the permitted slight turning of the dog on its pivotal support under the influence of the friction knobs associated with the latch bar as the latter is shifted.

The present device is simple in construction and mode of operation and is positive in its action. It is practical for the purpose described and for innumerable analogous uses. The accidental dropping of the raised desk to any extent is prevented by the automatic re-setting of the latch dog.

Having thus described my invention, what I claim as new therein, and desire to secure by Letters Patent, is:

1. In combination, a support, a movable top

member associated therewith for raising and lowering movements and a catch mechanism for the support of said top member when in a raised position; said catch mechanism comprising a rigid bar pivotally connected at one end to the said top member for endwise travel in accordance with its raising and lowering movements, said bar being formed with a longitudinal slot and with notches in spaced relationship along an outer edge thereof, a pivot shaft mounted in the support and extended through said bar slot as a guide for the bar in its endwise travel, a latch dog pivoted on the said pivot shaft and extended across the bar at one side of its longitudinal slot and beyond its notched edge, and formed at its outer end with a transversely directed part adapted to be selectively engaged in the bar notches to support the top member at definite raised positions of adjustment, and by angular adjustment of the latch dog relative to the bar to be disengaged from the notched edge of the bar for free travel of the bar, and means on the latch dog and on the bar that are frictionally engageable for the actuation of the latch dog to and from bar holding position by endwise movement of the bar in opposite directions.

2. A combination as in claim 1 wherein the latch dog comprises spaced opposite side plates with their inner ends mounted on the pivot shaft at opposite sides of the bar and their outer ends joined by said transversely directed part thereof; and wherein the said bar is slidable endwise between the opposite side plates of said dog.

3. A desk having a frame structure, a top member hinged thereto for raising to different angles of inclination, and a catch mechanism for support of said top member in a raised position; said catch mechanism comprising a rigid bar pivotally attached at one end to said top member at a substantial distance from the hinge and formed with a longitudinal slot and with notches in spaced relationship along one of its longitudinal edges, each notch providing a shoulder faced toward the free end of the bar, a pivot shaft fixed in the frame structure parallel with the hinge axis and substantially spaced therefrom, and passing through the bar slot as a guide for the bar in its endwise movements with the raising and lowering of the top member, 50 a latch dog comprising spaced opposite side plates with inner ends mounted on the pivot shaft at opposite sides of the bar, and extended beyond the notched edge of the bar and joined across their outer ends by a shoulder engaging cross member that is selectively engageable with the notch shoulders for support of the top member at definite angles of inclination, and is disengageable from the shoulders for the free endwise movement of the bar, spring members associated with the latch dog and outwardly yieldable from the bar, and contact members on the bar corresponding to each of the notches therein, and adapted, with the endwise movements of the bar to be engaged with said spring member to actuate the latch dog about the pivot shaft to move the said cross-member thereof to and from shoulder engaging position.

4. A combination as recited in claim 3 wherein, in upward adjustment of the hinged top member from a raised position of support, the engaging of a contact member of the bar with the said spring members of the latch dog, swings the latch dog from holding to released position.

5. A combination as in claim 3 wherein, in any upward adjustment of the hinged top mem-

ber, the engaging of a contact member with the said spring members of the latch dog, swings the latch dog to released position, and the engaging of the contact member with the spring means of the released latch in a downward adjustment of the raised top member, swings the dog to holding engagement with the shoulder of the notch corresponding to that contact member.

6. In combination, a longitudinally movable bar, formed in one edge with a stop shoulder, and having a longitudinal slot, a pivot shaft extended through the slot as a guide for the bar in its longitudinal movements, and a latch dog pivotally mounted on the shaft and comprising spaced opposite side members between which the bar is slidably contained; said side members being joined at their outer ends by a cross-piece adapted by an angular adjustment of the dog to be engaged with the bar shoulder to stop travel of the bar in one direction, a spring strip contained longitudinally of and between the side members of the latch dog for its angular adjustment and outwardly yieldable from the bar and by means of which strip the latch dog can be

swung on the pivot shaft between bar holding and bar releasing positions, a contact button on the bar adapted, in passing the dog, to engage frictionally with the said spring members, and by such engagement in one direction of movement of the bar, to swing the latch dog from a holding to a released position, and in moving in the opposite direction of travel, to swing the released latch to holding contact with the shoulder and a spring washer disposed under compression about the pivot shaft between a side member of the dog and said spring strip.
